(57) **CLAIM**

(**) Term: **15 Years**

The ornamental design for a portion of a brush head for an electric toothbrush, as shown and described.

(21) Appl. No.: **29/531,816**

(22) Filed: **Jun. 30, 2015**

DESCRIPTION

(63) Continuation of application No. 29/425,946, filed on Jun. 28, 2012, now Pat. No. Des. 734,613.

FIG. 1 is a front elevation view of a portion of a brush head for an electric toothbrush according to the new design; FIG. 2 is a rear elevation view thereof;

(30) **Foreign Application Priority Data**

FIG. 3 is an enlarged top view thereof;

Dec. 28, 2011 (JP) 2011-030439

FIG. 4 is an enlarged bottom view thereof;

(51) **LOC (10) Cl.** **04-02**

FIG. 5 is a right side elevation thereof;

(52) **U.S. Cl.**

FIG. 6 is a left side elevation view thereof;

USPC **D4/101**

FIG. 7 is front perspective view thereof, shown on a scale greater than that shown in FIG. 1 but less than that shown in FIGS. 3 and 4;

(58) **Field of Classification Search**

FIG. 8 is an enlarged rear perspective view of the design as shown in FIG. 7;

USPC D4/101, 104-112, 114; 15/110, 167.1, 15/167.2, 176.1, 176.6, 188, 22.1, 145; 132/308-311; 601/139, 141, 142

FIG. 9 is a rear view thereof, shown on a scale greater than that shown in FIG. 7 but less than that shown in FIGS. 3 and 4;
